CONTROL APPARATUS

Russell B. Matthews, Wauwatosa, Wis., assignor to Baso Inc., Milwaukee, Wis., a corporation of Wisconsin

Application November 14, 1955, Serial No. 546,623

23 Claims. (Cl. 137—66)

This invention relates, in general, to apparatus for controlling fluid flow, and the present application is a continuation-in-part of my application, Serial No. 329,599, filed January 5, 1953, and now abandoned.

While I have shown and shall describe herein as an illustrative embodiment of the present invention a safety shut-off embodying a pair of valves, one for one flow of fluid and the other for another flow of fluid, it is to be understood that the invention is not, in its broader aspects, limited to this particular embodiment but may be employed in connection with any suitable controlling members and for all similar purposes.

One of the main objects of the present invention is to provide in a device of the character set forth a first controlling member having first and second operating positions, a second controlling member having first and second operating positions, a power unit adapted to be energized by a source of electric energy, and means restrained from operation when the power unit is energized and operatively associated with the first and second controlling members for operating both said controlling members from their second to their first operating positions upon deenergization of the power unit.

Another object is to provide a device of the character set forth wherein the power unit is in the form of an electromagnet provided with an armature, and wherein there is means restrained from operation when the electromagnet and armature are held in attracted relation and operatively associated with the first and second controlling members for operating both controlling members from flow-permitting positions to flow-preventing positions upon deenergization of the electromagnet.

Another object is to provide a device of the character set forth wherein the electromagnet and armature are held in attracted relation when the electromagnet is energized by a source of electric energy and each has retractive movement away from the other upon deenergization of the electromagnet, and wherein one fluid flow controlling member is operable from flow-permitting position to flow-preventing position by the retractive movement of the electromagnet and the other fluid flow controlling member is operable from flow-permitting position to flow-preventing position by the retractive movement of the armature.

Another object is to provide a device of the character set forth wherein there is means biasing both the first and second controlling members from their flow-permitting positions to their flow-preventing positions, and wherein the electromagnet and armature therefor, when held in attracted relation upon energization of the electromagnet, restrain said biasing means, and wherein upon deenergization of the electromagnet the biasing means is released for movement of both controlling members from their flow-permitting positions to their flow-preventing positions.

Another object is to provide a safety shut-off for fluid fuel burning apparatus having a main burner and an ignition burner wherein there is a first valve having flow-

2

preventing position shutting off flow of fuel to the main burner and flow-permitting position permitting flow of fuel to the main burner, a second valve having flow-preventing position shutting off flow of fuel to the ignition burner and flow-permitting position permitting flow of fuel to the ignition burner, an electromagnet for energization from a source of electric energy and an armature therefor held in attracted relation by energization of the electromagnet, and means restrained from operation when the electromagnet and armature are held in attracted relation and operatively associated with the first and second valves for operating both valves from their flow-permitting positions to their flow-preventing positions upon deenergization of the electromagnet. This is advantageous in that it provides 100% shut-off of the fuel (i.e., shut-off of the fuel for both the main burner and the ignition burner) upon deenergization of the electromagnet, for example, by extinguishment of the ignition burner flame where the electromagnet is powered by a thermoelectric generator subject to the heat of such flame.

Another object is to provide a safety shut-off of the character set forth powered by its own internal source of electric energy such as that provided by a single thermocouple or by a thermopile or similar source of small electric energy and provides 100% safety shut-off in the manner set forth.

Another object is to provide a device of the character set forth wherein one valve member is carried by the electromagnet and the other valve member by the armature for movement of both valve members to their closed positions by separation of the electromagnet and armature from each other upon deenergization of the electromagnet such as takes place, for example, upon extinguishment of the ignition burner flame where the electromagnet is powered by a thermoelectric generator subject to the heat of the ignition burner.

Another object is to provide a device of the character set forth wherein the electromagnet is movable into operative association with one valve member to pick up said valve member for movement to open position when the electromagnet is energized, the other valve member being opened by movement of the electromagnet into operative association with the first mentioned valve member and there being means for manually resetting the electromagnet into operative association with the first valve member with accompanying movement of the other valve member to open position.

Another object is to provide a device wherein the main valve member which functions to shut off, for example, the flow of gaseous fuel to the main burner upon extinguishment of the ignition burner, is held closed, for example, to interrupt or shut off the flow of gaseous fuel to the main burner during the resetting operation.

Further objects and advantages and numerous adaptations of the invention will appear from the following detailed description taken in connection with the accompanying drawing showing two embodiments of the invention, it being understood that the invention is limited only within the scope of the appended claims and not to the particular embodiment selected for illustration.

In the drawings:

Figure 1 is a sectional view through a safety shut-off device embodying one form of present invention and showing more or less diagrammatically the same applied for shutting off the flow of fuel for both a main burner and an ignition burner and wherein there is a thermoelectric generator subject to the heat of the ignition burner for energizing the electromagnet;

Figure 2 is a fragmentary sectional view of the device of Figure 1 showing the hood assembly, electromagnet,

armature, pilot valve and main valve in energized position;

Figure 3 is a view similar to Figure 2 showing the unit in resetting position with the magnet frame in attracted relation with respect to the armature and the main valve in closed position; and

Figure 4 is a sectional view of a safety shut-off device embodying another form of the invention, the disposition of the parts thereof being similar to that of the corresponding parts in Figure 2.

In the embodiment of the invention illustrated in Figures 1 to 3 of the drawing, the numeral 1 indicates a valve body having a gaseous fuel inlet 2 and a gaseous fuel outlet 3. Contiguous sections of gaseous fuel supply pipe 4 are connected to the inlet 2 and outlet 3. The section connected to the outlet 3 leads, for example, to a main burner 5 which may be located in the firebox of a heater or fuel burning apparatus.

Internally the valve body 1 has a partition 6 defining a port 7 for placing the inlet 2 in communication with the outlet 3 for supply of gaseous fuel to the main burner 5. This port 7 is surrounded by an annular valve seat 8 upon which a main valve or control member 9 is adapted to seat to shut off the flow of fluid fuel to the main burner 5. Near the upper end of the upright part of the valve body 1 is a pilot fuel outlet 10 which is connected by a pilot fuel supply pipe 11 to supply gaseous fuel to a pilot or ignition burner 12 located in juxtaposition to the main burner 5.

A pilot fuel outlet chamber 13 opens from the interior of the gaseous fuel inlet chamber 14 to the pilot fuel outlet 10. The pilot outlet chamber 13 is surrounded by an annular valve seat 15 upon which a pilot valve 16 is adapted to seat to shut off the flow of fuel to the pilot burner 12. The valves 9 and 16 are preferably provided with yieldable or resilient facings 17 and 18, respectively, for cooperation with the respective valve seats 8 and 15.

The delivery of gaseous fuel from the pipe 4 to the main burner 5 is preferably by way of a mixing chamber 19 to which air is admitted through adjustable air inlets (not shown) as well understood in the art.

The pilot valve 16 is carried by an electromagnet 20 comprising a magnet frame 21 and a coil 22 wound around the legs thereof, for example, by attaching the base of the magnet frame 21 to the valve disc at 23. The valve disc has an outwardly projecting stem 24 which carries a pin 25 operating in a slot 26 in a reset stem 27. The reset stem 27 carries a reset button 28 at its outer end and a coiled spring 29 is interposed, for example, between the button 28 and the valve body 1 and biases the button 28 and reset stem 27 outwardly. Outward movement of the reset stem 27 is limited by engagement of stop shoulders 30 on the inner end thereof with an abutment 31 on the valve body 1.

An armature 35 cooperates with the electromagnet 20, and an electromagnet and armature cup or housing 34 encloses said electromagnet and armature and is suitably secured at 36 to the valve disc 16 and electromagnet 20 assembly for movement therewith as will presently appear. The armature 35 is carried by an armature stem 37 which extends for reciprocatory movement through an opening (which is preferably suitably sealed) in the end wall 38 of the cup or housing 34. The main valve disc 9 is carried on the opposite end of the stem 37 for movement therewith. A coiled spring 40 is interposed, for example, between the main valve disc 9 and the wall 41 of the valve body and acts upon deenergization of the electromagnet 20 to bias the valve 9 to closed position. Another coiled spring 42 is interposed between the valve disc 9 and the end wall 38 of the cup or housing 34, said spring acting in one direction against the armature 35 and valve member 9 and reacting in the opposite direction against the electromagnet 20 and valve member 18, biasing the electromagnet and armature toward

their initial positions in separated relation and the valve members 9 and 16 toward their closed or first operating positions.

The electromagnet is shown as powered by a single thermocouple 45 heated, for example, by the flame of the ignition burner 12, although a thermopile or other source of small or, if desired, greater electric energy may be employed. The thermocouple 45 comprises dissimilar thermocouple elements 46 and 47 joined at 48 to form a "hot" junction which is heated by the ignition burner flame. The thermocouple elements are connected in circuit with the coil 22 of the electromagnet 20 by lead conductors 50 and 51 for energization of the coil 22 by the thermocouple 45 when its "hot" junction is heated by the ignition burner flame.

The thermocouple 45 and lead conductors 50 and 51 may be of concentric form, the thermocouple comprising an outer tubular thermocouple member and an inner thermocouple member and the lead conductors comprising an outer tubular lead conductor joined to the outer thermocouple member and an inner lead conductor joined to the inner thermocouple member as disclosed in Oscar J. Leins Patent No. 2,126,564, patented August 9, 1938. In such case the concentric lead conductors may be detachably connected in circuit with the coil 22 of the electromagnet 20 by a detachable terminal connector means in the wall of the upright portion of the valve body 1 as disclosed in Henry J. Alfery Patent No. 2,276,909, patented March 17, 1942. The circuit connection between the thermocouple 45 and the coil 22 has been shown diagrammatically in the drawing of the present application.

The operation of the aforescribed embodiment of the invention is as follows:

When it is desired to ignite or reignite the main burner 5 with the parts in the deenergized shut-off position shown in Figure 1 of the drawing, the reset button 28 is engaged with the hand or fingers and pressed inwardly. The pin 25 being positioned at the outer end of the slot 26, this inward movement of the reset button 28 moves the valve disc 16 and electromagnet 20 assembly inwardly until the poles of the magnet frame 21 are brought into contact or attracted relation with respect to the armature 35, the end wall 38 of the cup 34 having sliding movement along the stem 37.

The inward movement of the reset button 28 is against the bias of spring 29 and also against the bias of spring 42 and the accompanying initial inward movement of the valve disc and electromagnet assembly moves the pilot or ignition valve 16 to a second operating position, i.e., a flow-permitting or open position. Continued inward movement of the reset button sets the poles of electromagnet frame 21 into coupled or attracted relation with respect to the armature 35 to further compress the springs 29 and 42 and place the parts in the "reset" position shown in Figure 3. As soon as the valve 16 is opened, the gas which enters at the inlet 2 flows through the inlet chamber 14 and out through the pilot fuel outlet chamber 13, pilot fuel outlet 10 and pilot fuel supply pipe 11 to the ignition burner 12 which may then be ignited, for example, by a match or lighted taper or by an electric igniter or otherwise as desired.

The magnet frame 20 and armature 35 may be termed coupling members, and the flux generating coil 22 may be termed means for coupling said members. As soon as the heat of the ignition burner flame on the "hot" junction 48 of the thermocouple 45 has energized the coil 22 of the electromagnet 20 sufficiently, the flux generated by said coil magnetically couples the armature 35 in attracted position or coupled relation with respect to the poles of the magnet frame and against the bias of the spring 42. The reset button 28 may then be released, and when the reset button is released after energization of the electromagnet, the spring 29 acting through the lost-motion connection afforded by the slot

26 and pin 25, withdraws the assembly including the valve disc 16, housing 34, electromagnet 20, armature 35 and main valve 9 outwardly as a unit against the bias of spring 40, and independent of spring 42 which remains compressed. The reset button 28, on release, moves outwardly to its initial position defined by engagement of shoulder 30 with abutment 31, but the unitary assembly is not moved therewith an equal amount due to the coaction therewith of the lost motion connection and spring 40. The bias of spring 29 moves the unitary assembly to the "on" or energized position shown in Figure 2 wherein the pilot valve disc 16 is spaced away from the pilot valve seat 15 a distance determined by the length of the slot 26, the pin 25, in this position of the device being at the bottom or inner end of the slot 26 to limit the effect of the biasing spring 40 on the unitary assembly and define the "on" position thereof. This movement of the unitary assembly, of course, also moves the valve member 9 away from its seat 8 to its second operating position, i.e., flow-permitting or open position, as shown in Figure 2. It is thus apparent that the springs 29 and 40, together with the lost-motion connection 25-26, afford positioning means for the parts in their "on" position, the abutment of the pin 25 with the lower end of the slot 26 affording a stop or stop means limiting the effectiveness of the spring 40 in biasing the unitary assembly when the parts are thus positioned.

Upon opening of the main valve 9, gaseous fuel passes through the outlet 3 and pipe 4 to the main burner 5 and is ignited therat by the ignition burner 12. With the unit in energized position as shown in Figure 2, the flow of gaseous fuel which is established by opening of valve disc 16 continues to the ignition burner.

Upon extinguishment of the ignition burner flame the electromagnet is deenergized and the electromagnet and armature are freed for movement away from each other to their initial separated positions. The springs 40 and 42 then move the main valve 9 to its first operating or closed position shutting off the flow of fuel to the main burner, and the spring 42, acting through its engagement with the wall 38 of the cup 34, moves pilot valve 16 to its first operating or closed position shutting off the flow of fuel to the pilot burner. There is thus provided 100% safety shut-off for both the main burner and the ignition burner upon the deenergization of the electromagnet 20 which occurs upon extinguishment of the ignition burner flame.

While the operation of the improved control apparatus has been described as including the resetting operation shown in Figure 3, it is within the concept of the present invention to utilize an electromagnet and armature assembly in which, upon energization of the electromagnet, the armature and electromagnet are moved from separated to attracted relation by magnetic attraction to thereby move the parts from the positions shown in Figure 1 to the positions shown in Figure 2 without any manual operation. Direct acting electromagnetic assemblies not requiring manual resetting are well known in the art.

It is also within the concept of the present invention to dispense with the lost motion connection between the stems 24 and 27 and the shoulders 30 if desired. With such an arrangement, the "on" position of the parts shown in Figure 2 is defined by selecting springs 29 and 40 of such strength that the forces thereof are balanced when the unitary assembly is positioned as shown in Figure 2.

Figure 4 shows a flow control device similar to that shown in Figures 1 to 3 having embodied therein another form of the invention within the basic concept thereof. In Figure 4 the parts indicated by primed reference characters correspond to similar parts in Figures 1 to 3 indicated by the same reference characters unprimed.

It will be observed that the position of the sub-assembly comprising the electromagnet 20', armature 35', and housing 34' is reversed from the position of the corre-

sponding sub-assembly in Figures 1 to 3, and that the pilot valve 16' is carried by the stem 37' whereas the main fuel valve 9' is carried by the electromagnet 20'. The housing 34' carries a plate 53 which may be fixed thereto and against which one end of the spring 40' abuts, the other end of said spring abutting a wall portion 41' of the valve body 1' surrounding the valve seat 8' as shown. The spring 40' biases the plate 53 toward stop means which may take the form of a pair of pins or of one or more suitable shoulder or abutment members 52 fixed within the valve body 1' for a purpose which will become apparent hereinafter. Reset means in the form of a stem 27' having an external button 28' biased outwardly by a spring 29' may be provided if the electromagnet and armature assembly is of the type requiring manual resetting. If, however, the electromagnet and armature do not require manual resetting, the aforementioned reset means may be dispensed with.

In Figure 4 the parts of the device are shown in the "on" or energized position corresponding to the "on" position of the device shown in Figure 2. The electromagnet 20' and armature 35' are magnetically coupled in attracted relation against the bias of the spring 42' which acts in one direction against said electromagnet and reacts in the opposite direction against said armature, said spring being substantially stronger than the spring 40' as will hereinafter appear. When the electromagnet and armature are thus coupled, the spring 40', independent of spring 42' which remain compressed, biases the unitary assembly, comprising the electromagnet, armature, housing 34', plate 53, pilot valve or control member 16' and main fuel valve or control member 9', in the direction away from the valve seat 8' and the plate 53 into abutment with the stop or stop means 52 which limits the effectiveness of the spring 40' and coacts therewith as positioning means for the unitary assembly, defining the aforementioned "on" position wherein the pilot valve 16' is spaced from the seat 15' and the main fuel valve 9' is spaced from the seat 8'. If desired, the stop means 52 may be omitted, in which case the "on" position of the unitary assembly is defined by the free length of the spring 40'. In such a case a spring 40' is used which has a free length equal to the spacing between the plate 53 and the wall portion 41' shown in Figure 4. Where the stop means 52 are used, the free length of the spring 40' may be greater than the aforementioned distance, since the stop means 52 prevents movement of the unitary assembly by said spring beyond the positions shown.

On deenergization of the electromagnet 20', the spring 42' uncouples the electromagnet and armature and moves each of said electromagnet and armature away from the other to thereby move the valves 9' and 16' to closed position. In so doing, the spring 42' overcalls the weaker spring 40', compressing the latter as the plate 53 and housing 34', together with the electromagnet 20' and valve 9', move toward the seat 8'. Closure of the valves 9' and 16' effects 100% shut-off of the fuel flow.

To manually reset the device shown in Figure 4, the reset button 28' is manually depressed to cause the stem 27' to engage the pilot valve member 16' and move said valve member and the armature 35' inwardly against the bias of the spring 42' until the armature 35' is in attracted relation with respect to the pole faces of the electromagnet 20'. While the pilot valve member 16' is opened during this movement, the main fuel valve 9' remains undisturbed in its closed position. Energization of the electromagnet 20' while the armature 35' is in attracted relation with respect thereto, magnetically couples said armature and electromagnet, and upon release of the reset button 28 and retraction thereof by the spring 29', the spring 40' acting against the plate 53, moves the unitary assembly in the direction away from the seat 8' to the "on" position shown, wherein the plate 53 en-

gages the stop means 52 and the valves 9' and 16' are in open positions.

The embodiment of the invention shown in the drawing is for illustrative purposes only and it is to be expressly understood that said drawing and the accompanying specification are not to be construed as a definition of the limits or scope of the invention, reference being had to the appended claims for that purpose.

I claim:

1. Apparatus for controlling fluid flow, comprising, first and second valve members each having flow-permitting and flow-preventing positions, an electromagnet and armature therefor relatively movable to attracted and retracted relation and operatively associated, respectively with said first and second valve members, first biasing means biasing said electromagnet and armature toward retracted relation, reset means for effecting positioning of said electromagnet and armature in attracted relation and one of said valve members to flow-permitting position, second biasing means operable independent of said first biasing means upon release of said reset means during energization of said electromagnet to effect movement of said electromagnet and armature as a unit to thereby move said other valve member to flow-permitting position, positioning means including a stop to limit the effectiveness of said second biasing means to thereby position said electromagnet and armature in an intermediate position to maintain both of said valve members in their flow-permitting positions, said first biasing means being operable upon deenergization of said electromagnet to effect retractive movement of said electromagnet and armature to thereby move both of said valve members to their flow-preventing positions.

2. Apparatus for controlling fluid flow comprising, first and second valve members each having flow-permitting and flow-preventing positions, an electromagnet and armature therefor, said first valve having operative connection with said electromagnet and said second valve having operative connection with said armature, reset means for moving said electromagnet into attracted relation with respect to said armature and simultaneously said first valve member to flow-permitting position, biasing means for retracting said reset means, said armature and electromagnet when energized tending to move as a unit with said reset means with movement of the latter to its retracted position, said second valve member moving to flow-permitting position with such movement, means including lost motion connection between said electromagnet and said reset means for maintaining said electromagnet and armature as a unit in an intermediate position as determined by said lost motion connection and in which position both of said valves are maintained in flow-permitting position, and means for moving said armature and electromagnet apart upon deenergization of the latter and thereby moving both of said valves to flow-preventing positions.

3. Apparatus for controlling fluid flow, comprising, first and second valve members each having flow-permitting and flow-preventing positions, an electromagnet and armature therefor, said first valve being operatively associated with said electromagnet and said second valve being operatively associated with said armature, reset means for placing said electromagnet and armature in attracted relation thereby moving one of said valve members to flow-permitting position, biasing means for retracting said reset means, a lost motion connection between said electromagnet and reset means, said armature and electromagnet when energized tending to move as a unit with said reset means with movement of the latter to its retracted position, the other of said valve members moving to flow-permitting position with such movement, means for maintaining said electromagnet and armature as a unit in an intermediate position as determined by said lost motion connection and in which position both of said valves are maintained in flow-permitting position, and means for

moving said armature and electromagnet apart upon deenergization of the latter and thereby moving both of said valves to flow-preventing positions.

4. Apparatus for controlling fluid flow comprising, first and second valve members each having flow-permitting and flow-preventing positions, an electromagnet and armature therefor, said first valve fixed to said electromagnet for control solely thereby and said second valve fixed to said armature for control solely thereby, reset means for moving said electromagnet into attracted position with respect to said armature and simultaneously said first valve member to flow-permitting position while maintaining said second valve in flow-preventing position, first biasing means for retracting said reset means, a lost motion connection comprising an elongated slot formed in said reset means and a pin operatively associated with said slot and having connection with said electromagnet, said armature and electromagnet when energized tending to move as a unit with said reset means with movement of the latter to its retracted position, said second valve member moving to flow-permitting position with such movement, second biasing means opposing said first biasing means and cooperating with said lost motion connection for maintaining said electromagnet and armature as a unit in an intermediate position as determined by the length of said elongated slot and in which position both of said valves are maintained in flow-permitting positions, and third biasing means for moving said armature and electromagnet apart upon deenergization of the latter and thereby moving both of said valves to flow-preventing positions.

5. Control apparatus comprising, a pair of oppositely disposed valve seats, a pair of valve members for co-operation respectively with said valve seats, a pair of relatively movable coupling members each carrying one of said valve members and having an attracted relative position with respect to the other coupling member wherein in said valve members are in closer proximity to each other than are said valve seats, releasable coupling means for coupling said coupling members when in their attracted relative positions, means for effecting disposition of said coupled coupling members in a position in which both of said valve members are in spaced relation to their respective valve seats, and means independent of said means for effecting disposition for moving said coupling members from attracted relative positions to separated relative positions whereby each of said valve members is moved into engagement with its respective valve seat.

6. Control apparatus comprising, a pair of oppositely disposed valve seats, a pair of valve members for co-operation respectively with said valve seats, a pair of relatively movable coupling members each carrying one of said valve members and having a coupled position wherein said valve members are in closer proximity to each other than are said valve seats, means for effecting disposition of said coupling members when coupled in a position in which both of said valve members are in spaced relation to their respective valve seats, and means independent of said means for effecting disposition for moving said coupling members from their said coupled position to separated relative positions whereby each of said valve members is moved into engagement with its respective valve seat.

7. Control apparatus comprising, a pair of oppositely disposed valve seats, means positioned intermediate said valve seats including a pair of valves for cooperation respectively with said valve seats, and a pair of coupling members fixed respectively to said valve members, said coupling members being relatively movable and having a separated position and coupled position wherein the distance between said valve members is less than the distance between said valve seats, means positioning said coupling members when coupled in a position in which both of said valve members are in spaced relation with respect to their respective valve seats, and means inde-

pendent of said positioning means for moving said coupling members from coupled position to their said separated relative positions whereby each of said valve members is moved into engagement with its respective valve seat.

8. Control apparatus comprising, a pair of oppositely disposed substantially coaxial valve seats, means disposed intermediate said valve seats including a pair of valve members cooperating respectively with said valve seats, biasing means normally urging said valve members apart and into engagement with their respective seats, and releasable coupling means opposing said biasing means and comprising a pair of coupling members each associated with one of said valve members and relatively movable with respect to each other and to said valve seats, and means for moving said coupling members into coupled relation and maintaining them when so coupled in a position intermediate said valve seats with said valve members out of engagement therewith, release of said coupling permitting said biasing means to effect engagement of said valve members with their respective seats.

9. Control apparatus comprising, first and second control members each having first and second operating positions, first and second coupling members rigidly fixed relative to said first and second control members respectively and each having an attracted position with respect to the other coupling member and a separated position with respect thereto wherein the respective control member is in its first operating position, first biasing means to bias both of said coupling members toward their separated positions, releasable coupling means for coupling said coupling members when in their attracted positions against the bias of said first biasing means for movement thereof as a unitary assembly, and positioning means operable independent of said first biasing means and including second biasing means operatively coacting with said coupling members, when coupled, to position said unitary assembly so that each of said coupling members retains its respective control member in its second operating position, said first biasing means on release of said coupling means, effecting movement of each of said coupling members towards its separated position for movement of each of said control members from its second to its first operating position.

10. Control apparatus comprising, first and second control members each having first and second operating positions, first and second coupling members rigidly fixed relative to said first and second control members respectively and each having an attracted position with respect to the other coupling member and a separated position with respect thereto wherein the respective control member is in its first operating position, first biasing means to bias both of said coupling members toward their separated positions, releasable coupling means for coupling said coupling members when in their attracted positions against the bias of said first biasing means for movement thereof as a unitary assembly, and positioning means operable independent of said first biasing means and including second biasing means operatively coacting with said coupling members, when coupled, and stop means limiting movement of said unitary assembly under the bias of said second biasing means to position said coupled coupling members so as to effect disposition of said control members in their second operating positions, said first biasing means on release of said coupling means, effecting movement of each of said coupling members towards its separated position for movement of each of said control members from its second to its first operating position.

11. Control apparatus comprising, first and second control members each having first and second operating positions, first and second coupling members rigidly fixed relative to said first and second control members respectively and each having an attracted position with respect to the other coupling member and an initial position in

separated relation with respect thereto wherein the respective control member is in its first operating position, first biasing means to bias both of said coupling members toward their initial positions, releasable coupling means for coupling said coupling members when in their attracted positions against the bias of said first biasing means for movement thereof as a unitary assembly, and positioning means operable independent of said first biasing means and including second biasing means operatively coacting with said coupling members, when coupled, to position said unitary assembly so that each of said coupling members retains its respective control member in its second operating position, said first biasing means on release of said coupling means, effecting movement of each of said coupling members towards its initial position for movement of each of said control members from its second to its first operating position.

12. Control apparatus comprising first and second control members each having first and second operating positions, first and second coupling members having separated initial positions and relatively movable to coupled relation operatively connected to said first and second control members respectively to effect disposition of said control members in their first operating positions when said coupling members are in their initial positions, biasing means to bias both of said coupling members toward their initial positions, and positioning means operatively coacting with said coupling members, when coupled, to position said coupling members independent of said biasing means so that neither one of said coupling members is in its initial position and said control members are in their second operating positions, said biasing means on uncoupling of said coupling members, effecting movement of each of said coupling members toward its initial position for movement of each of said control members toward its first operating position.

13. Control apparatus comprising first and second control members each having first and second operating positions, first and second coupling members having separated initial positions and relatively movable to coupled relation operatively connected to said first and second control members respectively to effect disposition of said control members in their first operating positions when said coupling members are in their initial positions, first biasing means to bias both of said coupling members toward their initial positions, and positioning means including second biasing means operatively coacting with said coupling members, when coupled, to position said coupling members independent of said first biasing means so that neither one of said coupling members is in its initial position and said control members are in their second operating positions, said first biasing means on uncoupling of said coupling members, effecting movement of each of said coupling members toward its initial position for movement of each of said control members toward its first operating position.

14. Control apparatus comprising, first and second control members each having first and second operating positions, first and second coupling members operatively connected to said first and second control members respectively and each having an attracted position with respect to the other coupling member and an initial position in separated relation with respect thereto for positioning the respective control member in its first operating position, biasing means to bias both of said coupling members toward their initial positions, releasable coupling means for coupling said coupling members when in their attracted positions against the bias of said biasing means for movement thereof as a unitary assembly, and positioning means operatively coacting with said coupling members, when coupled, to move said unitary assembly independent of said biasing means to a position wherein neither of said coupling members is in its initial position and said control members are in their second operating positions, said biasing means on release of said cou-

pling means, effecting movement of each of said coupling members towards its initial position for movement of each of said control members from its second to its first operating position.

15. Control apparatus comprising, first and second control members each having first and second operating positions, first and second coupling members operatively connected to said first and second control members respectively and each having an attracted position with respect to the other coupling member and an initial position in separated relation with respect thereto for positioning the respective control member in its first operating position, first biasing means acting against one of said coupling members and reacting against the other to bias both of said coupling members toward their initial positions, releasable coupling means for coupling said coupling members when in their attached positions against the bias of said first biasing means, and positioning means including second biasing means operatively coacting with said coupling members, when coupled, to move the same and stop means to limit the movement of said coupled coupling members under the bias of said second biasing means so that neither one of said coupling members is in its initial position and said control members are in their second operating positions, said first biasing means on release of said coupling means, effecting movement of each of said coupling members towards its initial position for movement of each of said control members from its second to its first operating position.

16. Control apparatus comprising, first and second control members each having first and second operating positions, first and second coupling members operatively connected to said first and second control members respectively and each having an attracted position with respect to the other coupling members and an initial position in separated relation with respect thereto for positioning the respective control member in its first operating position, biasing means to bias both of said coupling members toward their initial positions, reset means operable to effect relative movement of said coupling members to attracted relative positions against the force of said biasing means and movement of one of said control members from its first to its second operating position, releasable coupling means for coupling said coupling members when reset, and positioning means operatively coacting with said coupling members, when coupled, to position said coupling members independent of said biasing means so that neither one of said coupling members is in its initial position and said control members are in their second operating positions, said biasing means on release of said coupling means, effecting movement of each of said coupling members towards its initial position for movement of each of said control members from its second to its first operating position.

17. Control apparatus comprising, first and second control members each having first and second operating positions, first and second magnetic members operatively connected to said first and second control members respectively and each having an attracted position with respect to the other magnetic member and an initial position in separated relation with respect thereto for positioning the respective control member in its first operating position, biasing means acting against one of said magnetic members and reacting against the other to bias both of said magnetic members toward their initial positions, electromagnetic coupling means energizable to couple said magnetic members in their attracted relative positions when moved thereto against the bias of said biasing means, and positioning means operatively coacting with said magnetic members, when coupled, to position said magnetic members so that neither one of said magnetic members is in its initial position and thereby to dispose said control members in their second operating positions, said biasing means upon deenergization of said electromagnetic coupling means, effecting movement of each of said

magnetic members towards its initial position for movement of each of said control members from its second to its first operating position.

18. Control apparatus, comprising, first and second control members each having first and second controlling positions, first and second coupling members movable to coupled and separated relation and operatively associated respectively with said first and second control members, first biasing means biasing said coupling members toward separated relation, reset means for effecting positioning of said coupling members in coupled relation and one of said control members to its second controlling position, second biasing means operable upon release of said reset means while said coupling members are coupled to effect movement of said coupling members as a unit independent of said first biasing means to thereby move said other control member to its second controlling position, and positioning means including a stop to limit movement of said coupling members as a unit under the bias of said second biasing means to thereby define an intermediate position for said coupled coupling members effecting disposition of both of said control members in their second controlling positions, said first biasing means being operable upon uncoupling of said coupling members to effect retractive movement of said coupling members to thereby move both of said control members to their first controlling positions.

19. Control apparatus, comprising, first and second control members each having first and second controlling positions, first and second coupling members movable to coupled and separated relations and operatively associated respectively with said first and second control members, first biasing means acting against one of said coupling members and reacting against the other to bias said coupling members toward separated relation, reset means for effecting positioning of said coupling members in coupled relation and one of said control members to its second controlling position, means for coupling said coupling members when in coupled relation, second biasing means operable upon release of said reset means while said coupling members are coupled to effect movement of said coupling members as a unit to thereby move said other control member to its second controlling position, and positioning means including a stop to limit movement of said coupling members as a unit under the bias of said second biasing means to thereby define an intermediate position for said coupled coupling members effecting disposition of both of said control members in their second controlling positions, said first biasing means being operable upon uncoupling of said coupling members to effect retractive movement of said coupling members to thereby move both of said control members to their first controlling positions.

20. Control apparatus comprising first and second control members each having first and second operating positions, first and second coupling members having separated initial positions and relatively movable to coupled relation operatively connected to said first and second control members respectively to effect disposition of said control members in their first operating positions when said coupling members are in their initial positions, biasing means acting against one of said coupling members and reacting against the other to bias both of said coupling members toward their initial positions, and positioning means operatively coacting with said coupling members, when coupled, to position said coupling members so that neither one of said coupling members is in its initial position and said control members are in their second operating positions, said biasing means on uncoupling of said coupling members, effecting movement of each of said coupling members toward its initial position for movement of each of said control members toward its first operating position.

21. In control apparatus the combination of first and second coupling members having separated initial posi-

13

tions and relatively movable to coupled relation, biasing means to bias both of said coupling members toward their initial positions, and positioning means operatively coacting with said coupling members, when coupled, to position said coupling members independent of said biasing means so that neither one of said coupling members is in its initial position, said biasing means on uncoupling of said coupling members, effecting movement of each of said coupling members toward its initial position.

22. In control apparatus the combination of first and second coupling members having separated initial positions and relatively movable to coupled relation, first biasing means to bias both of said coupling members toward their initial positions, and positioning means including 15 second biasing means operatively coacting with said coupling members, when coupled, to position said coupling members independent of said first biasing means so that neither one of said coupling members is in its initial position, said first biasing means on uncoupling of said coupling members, effecting movement of each of said coupling members toward its initial position.

23. In control apparatus the combination of first and second coupling members having separated initial positions and relatively movable to coupled relation, biasing means acting against one of said coupling members and reacting against the other to bias both of said coupling members toward their initial positions, and positioning means operatively coacting with said coupling members, when coupled, to position said coupling members so that neither one of said coupling members is in its initial position, said biasing means on uncoupling of said coupling members, effecting movement of each of said coupling members toward its initial position.
